UNITED STATES PATENT OFFICE.

ALBERT MARSHALL PUTNAM, OF WOBURN, MASSACHUSETTS, ASSIGNOR
TO THE PUTNAM PUMP COMPANY, OF MAINE.

WATER-ELEVATING APPARATUS.

SPECIFICATION forming part of Letters Patent No. 555,122, dated February 25, 1896.

Application filed January 8, 1895. Serial No. 533,712. (No model.)

To all whom it may concern:

Be it known that I, ALBERT MARSHALL PUTNAM, a citizen of the United States, residing at Woburn, in the county of Middlesex and State 5 of Massachusetts, have invented certain new and useful Improvements in Water-Elevating Apparatus; and I do declare the following to be a full, clear, and exact description of the invention, such as will enable others skilled 10 in the art to which it appertains to make and use the same.

My invention relates to improvements in water elevating or pumping apparatus, and its novelty will be fully understood from the 15 following description and claim when taken in conjunction with the annexed drawings, in which—

Figure 1 is a vertical section of my improved apparatus. Fig. 2 is an enlarged 20 detail section of a portion of the pump.

Referring by letter to the drawings, B indicates the pump, and C the motor for actuating the pump.

As shown in Fig. 1 of the drawings, the 25 casing D of the pump B is of a special construction, being formed in two parts, and it comprises the base or main section E, in which is formed the receiving-chamber e, the piston-cylinders f, the ports g, connecting the 30 receiving-chamber e and the cylinders f, and the passages h leading from the piston-cylinders above the ports g and the section F, in which is formed the air or discharge chamber i. This section F is mounted upon 35 the section E between the cylinders f and is secured in any approved manner, and it is provided, as shown, with a nozzle j, whereby a ready connection of the discharge-pipe may be effected.

40 j' k indicate the upwardly-opening valves of the pump, which control the ports g and passages h, respectively, and m m' indicate the pistons which are arranged in the cylinders f, as shown. These pistons m m' are 45 connected to rods n, and these rods are connected in turn to the ends of a rocking-beam p, whereby it will be seen that when said beam is actuated the pistons will be reciprocated in their respective cylinders.

50 In the practical operation of the pump it will be seen that when one piston—the piston

m', for instance—moves upwardly, so as to draw water from the receiving-chamber e into its cylinder, the other piston, m, will move downwardly and seating the valve j' and 55 opening the valve k will force all of the water which it had drawn into its cylinder by its preceding upward stroke into the air or receiving-chamber i and out through the discharge-pipe. Thus, when the pump is in operation, the water is forced in a steady and 60 continuous stream, which is a desideratum.

G indicates the main frame of the motor of my improved apparatus. This main frame comprises, by preference, the upright bars g 65 and the transverse bolts r connecting the same, and it affords bearings for the several shafts H, I, J, K, and L comprised in the motor. The shaft H is provided with a crank s, which is connected by a pitman t to a crank-branch u of the rocking-beam p, and motion is transmitted from the drive-shaft K to said shaft H through the medium of the gear-wheel M on the shaft K, the pinion N and gear-wheel P on the shaft J, the pinion Q and 70 gear-wheel R on the shaft I, and the pinion S on the shaft H. The gear-wheel M is loosely mounted on its shaft K, but it is provided with a spring-pressed pawl T, adapted to engage the ratchet-wheel U, which is fixed on 75 the shaft. By this construction it will be seen that when the shaft K is rotated in the direction of the arrow the wheel M will also be rotated and motion will be transmitted to the pump through the medium of the train 80 of gearing described.

Mounted on the shaft K, but within the frame, is the gear-wheel Y. This gear-wheel meshes, as shown, with the pinion Z on the shaft L, and this shaft is provided, as shown, 85 with a crank M', whereby it may be readily rotated in the direction indicated by the arrow.

In order to prevent freezing of water in the 90 pump and consequent damage thereto, I provide the mechanism better illustrated in Fig. 95 2, through the medium of which any water that remains in the piston-cylinders f, after the pump has stopped, may be permitted to pass back into the well or other source of supply. This mechanism comprises the levers 100 a², which are fulcrumed upon hangers depending from the pump-casing, rods b² con-

nected to the outer ends of the said levers and extending through stuffing - boxes c^2 and adapted to engage the valve j' , a bar d^2 arranged between the conduits h and above the receiving-chamber e , rods e^2 connecting said bar d^2 and the inner ends of the levers a^2 , and a spring interposed between the upper wall of the chamber e and the bar d^2 and adapted to normally hold said bar and the parts connected therewith in the positions illustrated in Fig. 2. By reason of the construction described it will be seen that when the pump is not in operation, and it is desired to drain the water from the piston-cylinders f , it is simply necessary for the attendant to press downwardly upon the bar d^2 , when the valves j' will be raised and any water in the said cylinders f will be permitted to pass into and through the receiving-chamber e and back into the well or other source of supply.

Having described my invention, what I claim is—

The pump described comprising the base or main section E , having the receiving-chamber e , the piston-cylinders f , the ports g , connecting the receiving-chamber e , and the cylinders f , and the passages leading from the

piston-cylinders above the ports g , the section F , in which the discharge-chamber is formed, the upwardly-opening valves j , controlling the ports g , the upwardly-opening valves k , controlling communication between the passages h , and the discharge-chamber, pistons arranged in the cylinder f , the bar d^2 , arranged above the receiving-chamber e , and between the passages h , the levers a^2 , fulcrumed below the receiving-chamber e , rods connecting the inner ends of said levers and the bar d^2 , rods connected to the outer ends of the levers a^2 , and extending through the receiving-chamber e , and engaging the valves j' , and a spring interposed between the upper wall of the receiving-chamber e , and the rod d^2 , and adapted to normally hold the said bar and the rods connected therewith in such a position that they will not interfere with the operation of the valves when the pump is in use, substantially as specified.

In testimony whereof I affix my signature in presence of two witnesses.

ALBERT MARSHALL PUTNAM.
